UNITED STATES PATENT OFFICE.

CHARLES F. STODDARD, OF NEW YORK, N. Y.

PERFORATED MUSIC-SHEET.

1,367,638.

Specification of Letters Patent.

Patented Feb. 8, 1921.

Application filed February 21, 1914, Serial No. 820,129. Renewed June 24, 1920. Serial No. 391,551.

To all whom it may concern:

Be it known that I, CHARLES F. STODDARD, a citizen of the United States, and a resident of New York, county and State of New York, have invented an Improvement in Perforated Music-Sheets, of which the following description, in connection with the accompanying drawings, is a specification, like characters on the drawings representing like parts.

This invention relates to perforated music sheets for automatic musical instruments such as player-pianos. Among other objects the invention is intended to provide visible means to distinguish different perforations so as to indicate the different degrees of intensity with which the notes thereof are intended to be played.

The invention may be readily understood by reference to one practicable embodiment thereof shown for illustration in the accompanying drawing which represents a fragment of a perforated music sheet.

Referring to the drawing, the note perforations there shown are arranged for convenient description in two groups, an accompaniment group to the left, and a theme group to the right. It is preferred that each tone be sounded and held through desired duration, by a series of small perforations (such as the series 1) which are placed so close together, appropriately to the size of the tracker vent to be opened thereby, as to produce the effect of a single long perforation. The advantages of strength and durability of the music sheet arising from such use of small perforations in series, instead of continuous long perforations, are well known to those skilled in the art.

In the illustrative example, each series of perforations for a note is given a distinctive appearance, by which, for instance, a theme note and an accompaniment note may be distinguished; or one theme note may be distinguished from another intended to be played with a different intensity.

To exemplify means for this purpose, the accompanying drawing shows the series 1 of perforations provided with an accompaniment-distinguishing perforation 2 which may be conveniently of greater length than the other perforations 3—3 of the same group. Similar accompaniment-distinguishing perforations 4—4, 5—5, are shown as associated with the several accompaniment series.

The series of perforations for the theme notes as illustrated, are provided with theme-distinguishing perforations 6—6—6, 7—7—7, and 8. The theme-distinguishing perforations are preferably substantially different in appearance from the accompaniment-distinguishing perforations, so that the person utilizing the sheet may readily observe which series of perforations pertain to the accompaniment and which to the theme. It will be noted, also, that the theme-distinguishing perforations 6—6—6 are conspicuously shorter than the theme-distinguishing perforations 7—7—7; and that the latter are likewise conspicuously shorter than the theme perforation 8. Thus, different lengths of the perforations 6, 7 and 8, may be arranged to indicate different degrees of intensity intended for their corresponding notes. For instance, the short perforations 6 may indicate piano; the longer perforation 7 may indicate mezzo-forte; and the still longer perforation 8 may indicate forte.

From the foregoing illustrative example, it will be apparent to those skilled in the art, that the described arrangement for distinguishing perforations may be utilized to characterize a music sheet in such a way that the user may be kept informed of the intended intensities and relative intensities of tones, or of other characteristics desired to be given to the respective tones.

It is to be understood that the specific embodiment of the invention described above and shown in the drawings, is disclosed merely for purposes of illustration and that the scope of the invention is not limited to the precise details of construction and arrangement shown. On the contrary, the invention may be variously embodied within the scope of the subjoined claims.

Claims:

1. A music sheet comprising, in combination, perforations for playing accompaniment tones and theme tones, having different appearances to distinguish visibly between accompaniment playing perforations and theme playing perforations, and certain of the theme playing perforations having appearances different from each other to distinguish visibly between perforations for theme tones to be played with one intensity and perforations for theme tones to be played with another intensity.

2. A music sheet comprising, in combina-

- tion, a group of perforations for each of a plurality of accompaniment notes, each said group having an accompaniment-distinguishing perforation of different appearance 5 from the other perforations of the same group; and a group of perforations for each of a plurality of theme notes, each said theme group having a theme-distinguishing perforation of different appearance from the 10 accompaniment-distinguishing perforations.
3. A music sheet comprising, in combination, a group of perforations for each of a plurality of accompaniment notes; a group of perforations for each plurality of theme 15 notes; each said theme group having a theme-distinguishing perforation giving said group an appearance different from that of an accompaniment group, and different theme groups having theme-distinguishing 20 perforations of different appearance indicating differences in intensity intended for the respective corresponding theme tones.
4. A music sheet comprising, in combination, a group of perforations for each of a plurality of accompaniment notes, each said accompaniment-distinguishing perforation of different appearance from the other perforations of the same group; and a group of perforations 25 for each of a plurality of theme notes, each said theme group having a theme-distinguishing perforation of different appearance from the other perforations of the same theme group and also from the accompaniment-distinguishing perforations. 30
5. A music sheet comprising, in combination, a group of perforations for each of a plurality of accompaniment notes, each said accompaniment group having an accompaniment-distinguishing perforation of different appearance 35 from the other perforations of the same group; and a group of perforations for each of a plurality of theme notes, each said theme group having a theme-distinguishing perforation of different appearance from the accompaniment-distinguishing perforations, certain of the theme-distinguishing 40
- 45

perforations differing in appearance from each other to indicate corresponding different intensities for the respective theme 50 tones.

6. A music sheet comprising, a combination, a group of bridged perforations for each of a plurality of tones to be played, the initial perforations of respective groups 55 being of different lengths to indicate characteristics intended for the corresponding respective notes while producing the same mechanical effect.

7. A music sheet comprising, in combination, a plurality of groups of bridged perforations for each of a number of tones to be played, the initial perforations of one or more of said respective groups which may have the same mechanical effect being of a 65 character visibly different from that of the following perforations of the same group.

8. A music sheet comprising, in combination, a plurality of groups of bridged perforations for each of a number of tones to 70 be played, and means to indicate the respective playing intensities to be given to the notes sounded by the respective groups of perforations comprising initial perforations, of one or more of said respective groups 75 which may have the same mechanical effect, of a character different from that of the following perforations of the same group.

9. A music sheet comprising, in combination, a plurality of groups of bridged perforations for each of a number of tones to be played, the initial perforations of one or more of said groups which may have the same mechanical effect being longer than the following perforations to differentiate 85 the appearance of the advance end of each group from the remainder of the group.

In testimony whereof, I have signed my name to this specification, in the presence of two subscribing witnesses.

CHARLES F. STODDARD.
